UNITED STATES PATENT OFFICE.

HENRY R. HEYL, OF PHILADELPHIA, PENNSYLVANIA, ASSIGNOR TO THE AMERICAN PAPER BOTTLE COMPANY, OF PHILADELPHIA, PENNSYLVANIA, A CORPORATION OF PENNSYLVANIA.

MACHINE FOR COATING ARTICLES WITH PARAFFIN OR OTHER COATING MATERIAL.

1,042,914.

Specification of Letters Patent.

Patented Oct. 22, 1912.

Application filed August 23, 1909. Serial No. 514,810.

To all whom it may concern:

Be it known that I, HENRY R. HEYL, a citizen of the United States, residing in Philadelphia, Pennsylvania, have invented certain Improvements in Machines for Coating Articles with Paraffin or other Coating Material, of which the following is a specification.

My invention is especially adapted for use in coating paper bottles or other containers with paraffin, and the object of my invention is to so construct the machine that the bottle will be completely coated with paraffin in such a manner that the paraffin will be distributed evenly over the exposed surface of the bottle.

Another object is to paraffin the corners of the bottle in order to close all exposed cavities. A bottle of this type is intended primarily for use as a container for milk and other material which would deteriorate when contained in a vessel that is not absolutely clean, and a bottle of this type is used once and then discarded.

In the accompanying drawings,—Figure 1, is a longitudinal sectional view of my improved machine for paraffining paper bottles and other containers; Fig. 2, is an end view looking in the direction of the arrow, Fig. 1; Fig. 3, is a perspective view of one of the bottle carriers; Fig. 4, is a sectional view of one of the bottle carriers with the upper ends of the arms broken away; Fig. 5, is a perspective view of a portion of the knock-off arm.

A is a kettle containing the liquid paraffin; this kettle is surrounded by a casing A' in which are steam pipes C, and I preferably place water between the casing and the kettle, forming a water jacket; the steam coils heating the water, which keeps the paraffin in proper liquid condition.

B is an endless belt, made up of side chains and cross bars, the chains pass around foot-wheels D mounted on a shaft D' adapted to bearings carried by the frame of the kettle A. They also pass around belt-wheels E mounted on a shaft E' adapted to adjustable bearings on the casing F. Set screws e' are used for the purpose of regulating the tension of the belt. The belt also passes around large sprocket wheels G mounted on a shaft G'. This sprocket wheel is practically an idler and is used for directing the return

run of the belt in the proper path; so that the surplus paraffin from the bottles will drip directly into the kettle.

g, g', g² are other idlers for the belt, and these may be increased or decreased according to the length of the belt. The casing F is mounted on the kettle and is open at one end f for the introduction of the bottles, and is open at the opposite end f' for the discharge of the coated bottles.

Mounted on the bars of the belt B are a series of carriers b', each made as shown in Figs. 3 and 4 in the present instance having three arms b² with inturned portions clamped between two disks b³ and b⁴, by a bolt b⁵. By this arrangement the arms b² can be moved toward and from each other to fit bottles of different diameters, these arms are bent toward the center of the carriers at their outer ends.

i are the bottles, tapered in form in the present instance, the bottom of the bottle being at the narrow end.

An operator can stand in front of the machine and readily force a bottle over the arms of the carrier, the arms having sufficient spring in them to retain the bottle until it is forced off the arms by the knock-off device H consisting of a shaft H' having arms h' and projecting heads h² arranged to strike the edge of the bottle between the arms b², forcing it off the arms and discharging it into a trough f² open at the end, and the operator takes the bottle from this trough. The knock-off device is, in the present instance, actuated by hand and is controlled by a lever h³ to which is attached a rod h⁴, and this rod is provided with a suitable handle so that when the machine is at rest the operator can simply pull the handle and discharge the bottle. In some instances the knock-off device may be actuated by the operator at the rear end of the machine by simply extending the handle to that end of the machine.

I prefer to move the endless conveyer by hand so as to insure the proper placing of the bottles on the carriers, and the same operator that feeds the machine can operate the belt, and in the present instance I have shown a lever N pivoted on a shaft D' and provided with a pawl n, which engages with a ratchet wheel n' secured to the shaft D' so that on reciprocating the lever N the

shaft will be rotated intermittently in one direction and will move the belt so as to bring one row of carriers into position in front of the opening f at each movement of the lever.

In order to allow the paraffin to be absorbed by the paper of the bottle, I preferably provide a steam coil C' directly under the return run of the belt B , as indicated, and this coil may be connected separately or with the coil C , as shown by dotted lines, so that after the major portion of the paraffin has dripped from the bottle, and if there is any small amount remaining within the bottle, it is all accumulated in the bottom and by applying the heat directly under the bottle, as shown, this surplus will be taken up and absorbed by the bottle, so that by the time the bottle reaches the discharge point all the surplus paraffin is taken up and absorbed and a perfectly coated bottle is the result.

It will be noticed in referring to Fig. 1, that the kettle is so shaped that the bottles travel close to it and when the kettle is otherwise shaped guides are used so that it will be impossible for the bottles to become detached from the carriers in their travel through the paraffin.

I may make the endless conveyer of any width desired. In the present instance I have shown it of such a width that ten bottles can be placed side by side, but the capacity of the machine will depend materially upon the number of bottles made.

While I have shown a hand operated machine, it will be understood that it may be operated by power with the use of any well known mechanism.

The operation of the machine is as follows: The machine is set in motion and heat is applied, the operator stands in front of the machine, with a nest of bottles and takes one at a time from the nest and places it on the carrier, and when the carriers are filled the handle N is reciprocated, moving the bottles into the paraffin and bringing into position another set of carriers to be filled, and this operation is repeated.

It will be noticed that two sets of bottles remain submerged in the paraffin at each operation, one bottle remaining in the paraffin while two sets of carriers are being filled. This gives the paraffin sufficient opportunity to coat the bottles and when the bottles are moved to the next position they are directly above the kettle and at such an incline that the surplus paraffin within the bottles will drip out into the kettle. In

the next three movements the bottle is turned to a vertical position, yet always above the kettle, allowing the surplus paraffin sufficient time to drip back into the kettle, and any paraffin remaining on the outside of the bottles will drip onto the bottom

of the casing F and will be returned to the kettle over the inclined drainage apron f' .

When the bottle is in an upright position it is close to the heating coils and any surplus paraffin that would remain within the bottle is absorbed, due to the heat of the coils, and the bottom of the bottle becomes thoroughly coated and saturated with the paraffin, filling up any holes or cavities which may exist. When the bottle reaches the point directly above the opening f' the knock-off is actuated and the bottle is discharged into the trough f'' and the operator at that end of the machine can take the bottles, placing them again in nests of a given number, and pack them immediately in bags, or boxes, so that the bottles can be shipped to their destination with the least amount of exposure to the air, as it is essential in the manufacture of bottles of this type to practically sterilize them and keep them closed until used.

I claim—

1. The combination in a machine for coating the interior and exterior of bottles and other articles of a kettle, an endless belt having a foot wheel above the kettle and a head wheel some distance from the kettle, a guide wheel around which the belt passes as it leaves the foot wheel, fixed carriers on the belt arranged substantially at right angles to the longitudinal line of the belt, the guide wheel extending over a portion of the foot wheel so that the bottles will enter the liquid in a substantially horizontal position and as they are removed from the liquid they will be tipped a sufficient distance, due to the position of the guide wheel, to allow them to drain.

2. The combination in a machine for coating the interior and exterior of bottles and other articles, of a kettle, an endless belt having a foot wheel directly above the kettle, a head wheel some distance from the kettle, guide wheels for directing the belt in a substantially vertical path, fixed carriers on the belt for holding the bottles to be dipped in a position substantially at right angles to the run of the belt, the guide wheel for the return run of the belt extending over a portion of the foot wheel so that as the bottles leave the liquid in the kettle they will be inclined to allow a given quantity of the liquid to drain from the interior, after which they will assume a horizontal position as they are carried by the belt to the head wheel so as to allow the remaining liquid to settle in the bottom of the bottle to form a seal.

3. The combination in a machine for coating bottles or other articles with paraffin or like material, of a kettle, means for heating said kettle, a conveyer, a foot wheel directly above the kettle around which the conveyer passes, a head wheel at one side

of the kettle some distance from the foot wheel, a small guide wheel for the forward run of the conveyer and a large guide wheel for the return run of the conveyer, said conveyer being made up of two chains spaced apart with a series of cross bars extending from one chain to the other, a series of carriers mounted on each cross bar and arranged so as to hold the bottle or other article substantially at right angles to the longitudinal line of the conveyer, a casing inclosing the horizontal portion of the conveyer, the small guide wheel being set back of a vertical line drawn from the foot wheel so that the bottles will be fed into the liquid and so that the liquid will gradually flow into the bottle, the large guide wheel overhanging the foot wheel so that the bottles will be slightly tilted to allow them to drip before assuming a vertical position, the remainder of the liquid in the bottle forming a seal in the bottom of the bottle as it accumulates while traveling in a horizontal position, with means for discharging the

bottle from the carrier at the end of the return run of the conveyer.

4. The combination, in a machine for coating the interior and exterior of bottles and other articles, of a kettle, an endless belt having a foot wheel above the kettle and a head wheel some distance from the kettle, a guide wheel around which the belt passes as it leaves the foot wheel, fixed carriers on the belt arranged substantially at right angles to the longitudinal line of the belt, the guide wheel extending over a portion of the foot wheel so that the bottles will enter the liquid and as they are removed from the liquid will be tipped a sufficient distance, due to the position of the guide wheel, to allow them to drain.

In testimony whereof, I have signed my name to this specification, in the presence of two subscribing witnesses.
